DESIGN FOR AN ICE-CREAM CONE

Charles Reineke, Jr., St. Louis, Mo.

Application April 15, 1948, Serial No. 145,735

Term of patent 14 years

(Cl. D8—2)

To all whom it may concern:

Be it known that I, Charles Reineke, Jr., a citizen of the United States, residing in the city of St. Louis and State of Missouri, have invented a new, original, and ornamental Design for an Ice-Cream Cone, of which the following is a specification, reference being had to the accompanying drawing, forming a part thereof.

In the drawing:

Fig. 1 is a top plan view of an ice-cream cone, showing my new design;

Fig. 2 is an elevational view thereof;

Fig. 3 is a bottom plan view thereof, and

Fig. 4 is a fragmentary sectional view taken at line 4—4 of Fig. 1.

I claim:

The ornamental design for an ice-cream cone, substantially as shown.

CHARLES REINEKE, JR.
